UNITED STATES PATENT OFFICE.

WLADYSLAW CZARNECKI, OF PHILADELPHIA, PENNSYLVANIA.

NOZZLE.

1,099,028.

Specification of Letters Patent. Patented June 2, 1914.

Application filed July 9, 1913. Serial No. 778,100.

To all whom it may concern:

Be it known that I, WLADYSLAW CZARNECKI, a subject of the Emperor of Russia, residing in Philadelphia, Pennsylvania, have 5 invented certain Improvements in Nozzles, of which the following is a specification.

One object of my invention is to provide a novel structure particularly designed to discharge liquid in the form of a finely divided whirling spray, the design of the parts being such as to permit of its use either as a nozzle for a burner or as the discharge pipe of any apparatus designed to deliver liquid in the form of a spray.

15 Another object of the invention is to provide a relatively simple, efficient and substantial nozzle for delivering liquid in the form of a spray, whose parts shall be of such design as to permit of their convenient 20 examination, the device as a whole being of such a nature as to not be liable to get out of order or require repair.

These objects and other advantageous 25 ends I secure as hereinafter set forth, reference being had to the accompanying drawings, in which:—

Figure 1 is a side elevation of a nozzle structure constructed according to my invention; Fig. 2 is an elevation partly in section, further illustrating the device shown 30 in Fig. 1; Fig. 3 is a plan of the body of the nozzle; Fig. 4 is an enlarged fragmentary section illustrating the detail construction of the nozzle body.

35 In the above drawings, 1 represents the body of the nozzle which consists of a hollow base 2 having the general form of a nut and in addition provided with a hollow threaded portion 3 projecting from one of its faces.

40 This threaded portion terminates in a relatively narrow cylindrical part 4 surmounted by a conical end 5 and there are a series of holes or passages 6 leading from the hollow interior of the body so as to open on the 45 cylindrical surface of the part 4. These passages are straight and extend upwardly and outwardly, their lines being all tangent to a circle concentric with the axis of the nozzle structure, and all inclined in the same 50 general direction.

Mounted on the body 2 is a removable head 7 which also includes a polygonal base portion 8 adapted to seat on the nut-formed portion of the body, 1, said base portion being surmounted by a delivery end 9. This latter is hollow, being internally threaded

in order to fit upon the threaded part 3 of the body, and having an internal generally conical chamber 10 with uninterrupted uniformly inclined walls inclosing the cylindrical part, 4, of the body, said chamber, 10, being of such proportions that when the parts are assembled as shown in Fig. 2, its conical walls are spaced away from the cylindrical portion 4 and the conical portion 5 of the body. This hollow chamber terminates in a relatively narrow cylindrical outlet passage 11 whose outer end enters a divergent outlet passage 12.

With such an arrangement and construction of parts, liquid flowing under pressure through the interior of the body 1 is delivered in a series of outwardly and upwardly inclined lines, all inclined in the same direction around the axis of the nozzle. As a consequence, when the liquid enters the part of the chamber 10 formed by the portions 4 and 5 of the body and the head 7, it has a divergent rotary movement which to some extent very effectually breaks it up into relatively fine drops or particles. It is then discharged through the passage 11 and the divergent opening 12, so that it is delivered in the form of a more or less solid cone or spray whose apex is substantially coincident with the outer end of the passage 11. Owing to the inclination of the passages 6, the particles of liquid in this conical body or sheet of spray have a more or less rotary movement, so that when the apparatus is used as a burner, the particles of liquid fuel delivered are of such fineness as to be efficiently and rapidly burned, it being noted that the process of combustion is greatly aided by the intimate mixture of air and liquid particles, resulting from the rotary and divergent paths given the particles of such liquid as these leave the nozzle. When liquid under pressure is delivered from these openings, it strikes the adjacent uniformly inclined walls of the chamber 14 and in view of the inclination of the said 100 passages, is given an interrupted rotary advancing movement so that when it finally passes through the outlet of the chamber 4, it is delivered in the form of a rotary and more or less divergent, finely divided spray.

I claim:—

The combination in a nozzle of a tubular body having a nut-formed portion constituting a shouldered base, and a threaded part terminating in a cylindrical portion

surmounted by a conical extremity there being upwardly and outwardly inclined passages from the interior of the body opening on the cylindrical portion thereof, with a 5 head also having a nut-shaped base and interiorly threaded to fit on the threaded part of the body, and to seat directly on the nut-formed portion thereof, the interior of said head having uninterrupted inclined 10 walls inclosing the cylindrical portion of said threaded part and extending upwardly

from its threaded part at an angle different from that of the conical end of the body, and having an outlet passage at its apex.

In testimony whereof, I have signed my 15 name to this specification, in the presence of two subscribing witnesses.

WLADYSLAW CZARNECKI.
